UNITED STATES PATENT OFFICE

1,987,219

FOLDING IRONING TABLE

Charles W. Sadenwater, Saginaw, Mich., assignor
to Saginaw Manufacturing Co., Saginaw, Mich.,
a corporation of Michigan

Application September 30, 1933, Serial No. 691,603

3 Claims. (Cl. 68—10)

My invention relates to folding ironing tables of the type in which an ironing board is provided with collapsible legs that can be folded up parallel with the board for storing.

More particularly, the invention pertains to such tables wherein the ironing board has pivoted to its under side a centrally arranged front leg and a pair of rear legs, with connecting rods pivoted to the front leg near its foot and pivoted to the rear legs intermediate their ends. There is also a locking rod member pivotally connected with the rear legs intermediate their ends. Tables of that kind are illustrated and described in United States Patent No. 1,627,556 issued to Henry J. Gilbert, wherein the locking rod member is shown and described as being slidably connected with the front leg by means of a collar or common locking member slidably mounted on the central member of the front leg, this leg member being preferably made of metal tubing.

My present invention relates to certain details of construction of the locking rod member, and of the front leg and associated parts, which details are designed to simplify the construction shown in the said patent, and which shall provide maximum strength and stability while enabling the leg structure to be made of wood instead of metal tubing, thereby reducing the cost and facilitating the manufacture and assemblage of the parts, with consequent economy in the production of the article.

I have found that a slidable sleeve connection between the locking rod member and the front leg, as exemplified in the earlier structure is entirely satisfactory when the front leg is made of metal tubing, but is not commercially practicable when the leg is of wood, because of the likelihood of swelling, shrinking or warping. My improvement, therefore, is directed to a structure wherein the desired folding and unfolding movements of the supporting structure can be accomplished without using any sleeve or equivalent member that is required to slide lengthwise along the front leg in order to permit the legs and braces to unfold or to be folded up flatwise against the under side of the board.

My invention also includes a novel means whereby the locking rod member is enabled to latch itself to the front leg when the table is extended for use, to insure against accidentally folding up the legs, and to make it easy for the user to unlatch the parts and so permit them to be folded up for storing.

With those objects in view and certain others that will appear later in the specification, I have

devised and invented the ironing board that is illustrated in the accompanying drawing and described in detail hereinafter, my invention residing in the particular construction and arrangement of the locking rod members and the manner in which they are hinged and connected to the front leg.

In my co-pending application of even date herewith, Serial No. 691,602, I have shown and described a folding ironing table of this character which is particularly strong, stable and efficient, and in certain respects is similar to that herein-after described. In the present application, however, I have claimed the features of construction common to both applications and believed to be patentably novel.

In the accompanying drawing, Figure 1 is a side view of the table with the legs extended to working position, an intermediate or partly folded position of the legs and the locking members being indicated diagrammatically by broken lines.

Figure 2 is a fragmentary enlarged detail of the structure whereby the table is extended for use.

Figure 3 is a perspective view of the latching member.

The same reference characters indicate the same parts in the several views.

Numeral 1 designates the ironing board to which is pivotally connected the centrally arranged front leg 2 and a pair of rear legs 3. Connecting rods 4 are pivoted at 5 to the front leg 2 near its foot and are also pivotally connected with the rear legs at 6. The locking rod member consists of two divergent bars 7 pivotally connected with the rear legs intermediate their ends, as at 35 pivots 6.

The means embodying my invention whereby the front ends of the bars 7 are operatively connected to the front leg 2 will now be described. Each bar 7 is pivoted at 8 to a side bar 9 of a latching member, shown in perspective in Fig. 3. The side bars 9, 9 are spaced apart sidewise so as to receive the front leg 2 between them. Adjacent the pivots 8 the bars 9, 9 are connected together in their spaced relation by a member 10 that also serves as a latch by which the locking rod member, made up of bars 7, 7, is releasably fastened to the leg 2 when the table is extended for use. The other ends of bars 9, 9 are pin-and-slot connected to leg 2 intermediate its ends, the pin being designated by numeral 11, the slot by 12.

Near the pivotal connection of leg 2 with the board 1, the leg is provided with an upwardly directed detent member 13, and a cut-away por-

tion 14 beneath the lip of the detent to releasably receive the bottom edge of latch member 10, and thereby fasten the leg 2 and bars 7, 7 together in locked relation when the table is in use.

- 5 5 To unlock the latch connection preparatory to folding up the table, the members 7 and 9 are lifted up at their pivotal connection 8, thus disengaging member 10 from member 13. The parts 7 and 9 then become in effect parts of a toggle joint 6, 8, 11. The joint 8 is urged downwardly as indicated by the arrow, Fig. 1, past its fully extended or straight position 8'. Meanwhile the front and rear legs have assumed the positions shown by the broken center lines. Having passed the 10 15 position 8' the toggle members are flexed in the opposite sense and the front leg 2 and rear legs 3, connected by the rods 4, swing toward the left, into the folded position 8'', 11'' underneath the board as shown in dotted lines. Meanwhile the 20 25 bars 9 have continued their movement of rotation in the direction of the arrows, Fig. 1, through about half a circle, until the bars 9 have been alined with the leg 2, clasping its sides so as to assist in holding it centrally against the under side of the board.

It is now plain that the structure above described provides a means for firmly locking the toggle rods 7, 7 to the top end of leg 2 and thus presenting a non-racking framework made up of 30 35 triangular reinforcing elements that are well arranged to insure stability of the entire framework. It also provides means for moving the convergent ends of rods 7, 7 from their locked position 8, around through 8' to the folded position 8'', without requiring them to slide lengthwise of the leg 2, which would have necessitated the use of a metal tube for the front leg and a sliding tubular sleeve at the ends of members 7. My present arrangement provides a simple, less expensive and 40 equally effective structure that enables the legs and rods to be made of wood, and can not be affected by warping or swelling.

Having thus described my invention, what I claim and desire to secure by Letters Patent is:

1. A folding ironing table having a board to which is hinged a pair of rear legs and a central front leg and connecting rod means pivoted to the front leg and also to the rear legs, said table also including locking rod members pivotally connected to the rear legs intermediate their ends in combination with a latching toggle member having an end pivotally connected to the front 10 leg and adapted for endwise movement thereon, said toggle member being pivotally connected at its other end to the ends of said locking rod members, and latching means adapted to releasably fasten the said toggle member to the front leg at 15 a point adjacent the hinged end of said leg.

2. In a table having foldable rear legs and a central foldable front leg pivoted to an ironing board, the said legs being operably joined by connecting rods, means for locking said parts in their 20 25 extended position, said means comprising a toggle joint pivotally connecting the rear legs at points intermediate their ends, with the said front leg, there being a latch member on the toggle adjacent its middle joint and a complemental latch member on the front leg adjacent its hinge.

3. In a table having foldable rear legs and a central foldable front leg pivoted to an ironing board, the said legs being joined by connecting rods, means for keeping said parts in their extended position and for permitting them to be folded flatwise against the board, said means consisting of a pair of locking rod members pivotally connected to the rear legs, and a bar member pivoted at one end to the front leg and pivoted at its other end to the convergent ends of said locking members whereby there is presented a toggle joint, and a latch associated with said bar member and adapted to releasably secure said toggle joint to the front leg.

CHARLES W. SADENWATER.
